UNITED STATES PATENT OFFICE.

FRANK W. SMITH, OF GARDNER, MASSACHUSETTS.

DESIGN FOR A HANDLE FOR SPOONS OR SIMILAR ARTICLES.

SPECIFICATION forming part of Design No. 34,917, dated August 13, 1901.

Application filed June 25, 1901. Serial No. 66,014. Term of patent 14 years.

To all whom it may concern:

Be it known that I, FRANK W. SMITH, a citizen of the United States, residing at Gardner, in the county of Worcester and State of Massachusetts, have invented and produced a new and original Design for Handles for Spoons or Similar Articles, of which the following is a specification, reference being had to the accompanying drawings, in which—

10 Figure 1 is a view of the obverse face. Fig. 2 is a view of the reverse face. Fig. 3 is a section on line 3 3 of Figs. 1 and 2.

As shown in the drawings, the leading or material feature of my design consists of a handle whose body portion has sides each 15 with a scroll and groove effect, the upper ends of the side scrolls and grooves being united by a double leaf surmounted by a triple bead and the lower ends by a double leaf and each 20 of these scrolls constituting one side of the body portion having a foliage effect in harmony with the leaves, while the shank portion of the handle has a grooved and ribbed effect, but also with an effect of foliage like 25 that on the sides of the body portion, and the junction of the shank and bowl repeats the double-leaf and side-scroll effect of the body portion.

The body portion *a* terminates at top in a 30 conventionalized leaf *a'*, with a high ribbed effect in front, and a like leaf *a²*, but with a sunken ribbed effect in rear, these leaves *a'* *a²* having in place of a stem a smaller leaf *a³* *a⁴*, the leaf *a⁴* with a high ribbed effect

and the leaf *a³* with a sunken ribbed effect. 35 The leaves *a'* *a²* merge into the scrolls *a⁵* *a⁶*, which flow into the double leaf *a⁷*, which forms the lower end of the body *a* in front, and into the double leaf *a⁸*, which forms the lower end of the body *a* in rear. 40

The shank *b* has a middle groove *b'* and two side grooves *b²* in front and two other shorter grooves *b³* in the wider upper part of the shank, while in the rear the middle groove *b⁴* is wider than the middle groove *b'* of the front 45 and widens as it extends toward the body portion, the grooves leaving well-defined ribs between them.

The portion *d* in front terminates in a double leaf *d'*, with a double scroll *d²* at the meeting 50 of the two leaves, forming the double leaf *d'*, and in the rear a similar double leaf *d³* and scroll *d⁴*, the lower leaf of double leaf *d³* resting on the stem portion of a larger leaf *d⁵*, which overlays the heel of the bowl. 55

Having described my invention, what I claim as new, and desire to secure by Letters Patent, is—

The design for a handle for spoons or similar articles as herein shown and described. 60

In testimony whereof I have signed my name to this specification in the presence of two subscribing witnesses.

FRANK W. SMITH.
